UNITED STATES PATENT OFFICE.

BENJAMIN GARTSIDE GILBOUGH, OF CHICAGO, ILLINOIS.

SPARKING DEVICE.

No. 801,452.

Specification of Letters Patent.

Patented Oct. 10, 1905.

Application filed December 30, 1904. Serial No. 238,927.

To all whom it may concern:

Be it known that I, BENJAMIN GARTSIDE GILBOUGH, a citizen of the United States, residing at Chicago, in the county of Cook and State of Illinois, have invented new and useful Sparking Devices, of which the following is a specification.

My present invention relates to ignition or sparking devices for the same general purpose as the one described in my application, Serial No. 238,926, of even date herewith.

My primary object is to provide an ignition device of exceedingly simple construction and great certainty of operation.

My invention is illustrated in the accompanying drawings, in which—

Figure 1 is a sectional view of an engine-cylinder with my improved ignition device applied thereto; Fig. 2, a plan view of a motive wheel employed; Fig. 3, a section taken as indicated at line 3 of Fig. 1, and Fig. 4 an illustration of the internal contact members viewed as indicated at line 4 of Fig. 1.

In the preferred construction illustrated, A represents the cylinder of an engine, and B my improved ignition device applied thereto.

The ignition device comprises a casing or shell b, having a threaded hollow stem screwed into a threaded opening in the cylinder; a core b' within said casing and electrically separated therefrom by insulations b² b³; a rotary wheel b⁴, surmounting the core and connected with a shaft b⁵, whose lower end projects into the engine-cylinder and is equipped with lateral contact or electrode points b⁶; a contact member or electrode b⁷, secured to a shaft b⁸, extending through a vertical perforation in the stem of the casing; a spring b⁹, secured to the internal surface of the casing and serving, through the medium of the shaft b⁸, to hold the contact member b⁷ in a given position; a casing-top b¹⁰, equipped with a stud b¹¹, bearing on the upper end of the shaft b⁵; a battery b¹², having a conductor b¹³, connected with the casing-top, and a conductor b¹⁴, connected with the engine-cylinder, and a make-and-break device b¹⁵, comprising a cam b¹⁶, operated from the engine-shaft, and a contact member b¹⁷, coacting with said cam. The wheel b⁴ is provided with an inner series of fan-blades b¹⁸, beveled or inclined in one direction, and an outer series of blades b¹⁹, beveled or inclined in the opposite direction. The core b' is provided with a passage b²⁰, which leads to the inner set of blades of the wheel, and the cas-

ing-top is provided with an outlet-channel b²¹, which registers with the channel b²⁰ and is provided with a suitably-confined upwardly or outwardly opening ball-valve b²². The casing-top is provided with an intake-passage b²³, 60 which registers with the outer set of blades of the wheel, and the core is provided with a passage b²⁴, which registers with the outer series of blades and is equipped with a downwardly or inwardly opening suitably-confined 65 ball-valve b²⁵.

From the foregoing detailed description the manner of operation will be readily understood. The wheel b⁴ rotates continuously in one direction, being operated by the passage 70 of gas through the channel b²⁰ during the time that the engine-piston is making its working stroke and its compression stroke and being operated by the intake of air through the passage b²³ when the engine-cylinder is being 75 charged. The make-and-break device b¹⁵ operates to make and break the external portion of the electric circuit at regular intervals in the usual manner, and at each half-revolution of the wheel b⁴ the internal portion of the electric circuit is made and broken at the contact members b⁶ b⁷. It may be observed that the internal portion of the electric circuit is continuously made and broken, while the external portion of the circuit is made at proper 85 intervals to deliver the current for producing a spark at the exact instant required in the operation of the engine.

While it is preferred to operate the internal rotary contact member by means of gas-pressure or gas and air pressure in the manner shown, still said contact member may be continuously rotated in any desired manner. The construction obviates the necessity of employing secondary circuits and electromagnets, 95 with the attendant disadvantages thereof, and the construction is peculiarly advantageous when used in connection with high-speed engines.

Changes in details of construction within 100 the spirit of my invention are feasible. Hence no undue limitation should be understood from the foregoing description.

What I regard as new, and desire to secure by Letters Patent, is—

1. The combination with an engine-cylinder 105 of an ignition device connected therewith, comprising a fluid-actuated rotary wheel, an electrode actuated by said wheel, a coacting electrode, an electric circuit completed 110

- through said electrodes, and means for making the external portion of the circuit at proper intervals, for the purpose set forth.
2. An ignition device for the purpose set forth, comprising a casing, an insulated core provided with a fluid-passage, a wheel having blades registering with said passage, an electrode actuated by said wheel and an electrode carried by said casing.
- 10 3. An ignition device for the purpose set forth, comprising a casing and a core having valved inlet and outlet passages, a wheel having two oppositely-disposed series of blades registering respectively with the inlet and outlet passages, a rotary electrode actuated by said wheel, and a coating electrode connected with the casing.
- 15 4. An ignition device for the purpose set forth, comprising a casing having a removable cap and a hollow threaded stem, a core within said casing provided with a passage, the top having a passage registering with said first-named passage, a wheel located between the core and the casing-top and having blades registering with said passages, a shaft connected with said wheel and extending through said core, said shaft bearing a contact-electrode, and a contact-electrode connected with the casing.

BENJAMIN GARTSIDE GILBOUGH.
